Inventor,

Arthur M. Benner.

UNITED STATES PATENT OFFICE.

ARTHUR M. BENNER, OF OLYMPIA, WASHINGTON.

POCKET MATCH BOX.

Application filed January 9, 1923. Serial No. 611,654.

To all whom it may concern:

Be it known that I, ARTHUR M. BENNER, a citizen of the United States, residing at Olympia, in the county of Thurston and State of Washington, have invented a new and useful Pocket Match Box, of which the following is a specification.

My invention relates to improvements in pocket match boxes, in which matches are carried in the pockets of one's clothing or in a hand bag; and the objects of my improvement are, first, to eliminate several complications of a similar improvement specified in application, No. 462,326, for patent on a pocket match box filed April 18, 1921, by myself and son, George M. Benner; second, to produce a pocket match receptacle that, although housing an operating mechanism, contains a maximum number of matches, which, due to the novel operation of said mechanism, may be used one at a time with no danger of spilling the remaining matches, and without experiencing any of the inconveniences of the ordinary box such as inserting thumb and finger in the mouth of the box, or shaking the matches part way out that a match may be grasped; and third, to effect an assemblage of interior parts that they may be lifted from the box, intact as one piece, for cleaning or repairing.

I attain these objects by a mechanical device, an inner casing, a raised floor, and a slitted elastic which covers an opening in said box's cover; all being illustrated in the accompanying drawings, in which—

Figure 1 is a vertical view of a mechanical device as shown by removing the adjacent end wall of the box;

Fig. 2 is a longitudinal, vertical section of the match box and mechanical device;

Fig. 3 is a vertical view of the mechanical device from the interior of the box;

Fig. 4 is a plan of the box and interior parts;

Fig. 5 is a top view of the box's cover, with transverse and longitudinal vertical sections thereof;

Fig. 6 is plan and elevations of the raised floor; and

Fig. 7 is a perspective view of the inner casing.

Similar numerals refer to similar parts throughout the several views of the drawing.

The interior of this pocket match box comprises two vertical chambers; one very narrow 8 (Fig. 4) containing said mechanical device, and the other AB very large, having its interior broken near the center by bent-in ends 9 of an inner casing.

Matches in said box, be they few or many, must be approximately upright therein; therefore, to utilize chamber AB, whose length exceeds that of a match, said bent-in ends 9 of said inner casing are used, which also allow said matches to shift from A to B, and vice versa, thus eliminating the sliding partition used in the former box referred to in the oath herewith.

Said inner casing Fig. 7 has side walls 10, one complete end wall 11, and the said bent-in ends 9. In said end wall 11 is a vertical groove 12 (Figs. 4 and 7), containing a longitudinal slot 13 (Fig. 7).

Said inner casing (Fig. 7) is secured to the said raised floor 6 (Figs. 2 and 6) by projections 14 (Figs. 2 and 7) which protrude through corresponding openings 15 (Fig. 6) in said raised floor 6, and are clinched against, or soldered to, the under surface of said floor.

The said mechanical device, or operating mechanism, consists of a lazy tongs 16 (Figs. 1 and 3), a spring 17 (Fig. 1), a slotted foot 85 attachment 18 (Fig. 3), and a slotted connecting bar 19 (Fig. 1).

The lower first joint 20 (Fig. 3) of said tongs 16 is pivoted to an upwardly-bent end 21 of said raised floor 6. To the upper and last joint 22 (Fig. 3) is pivoted the upper end of the said foot attachment 18 whose toe portion 23 (Fig. 3) extends through, and plies within, the said slot 13 (Figs. 4 and 7). The upper surface of this toe 23 is sharp-shod, and is just below the upper surface of the said raised floor 6 when the said operating mechanism is at rest.

Between the said lazy tongs 16 and the adjacent end wall of said box's outer casing, is the said connecting bar 19 whose lower end is pivoted to the lower end 24 of said tongs 16, and to whose upper extremity is attached a finger-engaging member 25 (Fig. 2) whose neck element 26 plies in a slot 27 in said end wall of said outer casing.

The said spring 17 (Fig. 1) rests between the lower ends of the said tongs 16 and connecting bar 19, and the bottom of the match box. By pressing downward on the said

finger-engaging member 25, said tongs is forced open in the opposite direction, thus lifting said foot 18 as many times higher than said finger-engaging member is pressed downward as there are joints in said tongs above its fulcrum point 20 (Fig. 3), and said spring 17 is tensioned sufficiently that on releasing said finger-engaging member 25, said mechanism is brought to its original position by said spring.

The said spring 17 may be omitted and the said mechanism be allowed to function by force of gravity, although the spring is surer and safer.

35 The said lazy tongs 16 is guided and held in its proper vertical movement by one of its upper assembling rivets 28 (Fig. 1) which plies countersunkly in a slot 29 in the said connecting bar 19. The said foot attachment 18 is guided likewise by the next lower assembling rivet 30 (Fig. 3).

25 The cover (Fig. 5) of this match box has its rim deeply channeled, 31 (Fig. 5), to snugly engage the rim of said box, and has pivoted thereto a friction latching member 32 whose ends are swung through openings in the inner wall 33 of said channel 31, and into openings 34 (Fig. 2) in the upper end of the side walls of said box.

30 In this cover (Fig. 5), directly opposite the said groove 12 in the end wall 11 of the said inner casing, is an opening which is covered by at least one thickness of a slotted elastic 35 (Fig. 5), through which a match 35 may be pushed, and which affords enough friction to prevent said match from being entirely ejected from said match box.

I am not aware that prior to my invention a pocket match box such as mine has ever 40 been patented, or described in any publication.

In this match box, I do not claim the outer casing, the lazy tongs, the spring, or the finger-engaging member, but

45 I claim:

1. In a pocket match box, a foot attachment having a longitudinal slot therein, and whose toe portion is sharp-shod on its upper surface.

50 2. In a pocket match box, the combination of a foot attachment with a raised floor and a lazy tongs, said tongs being pivoted at a lower joint to an upwardly-bent end of said floor, and said foot being pivoted by its upper end to the upper end of said tongs,

its lower end, or toe portion, plying within an opening in said floor.

3. In a pocket match box, the combination of a foot attachment with a raised floor, a manually-operated member, and a spring-actuated lazy tongs, a lower joint of said tongs being pivoted to an upwardly-bent end of said floor, said manually-operated member having its lower end pivoted to the lower end of said tongs its upper end plying within a slot in an end wall of said box, said foot attachment having its upper end pivoted to the upper end of said tongs, longitudinal alignment of said tongs while in motion being effected by the head of an elongated assembling rivet of said tongs which plies countersunkly within a longitudinal slot in said manually-operated member, and said foot being held in alignment by another tongs rivet which plies within a slot therein. 75

4. In a pocket match box, the combination of a manually-operated member, a spring-actuated lazy tongs, a raised floor, and an inner casing attached to said raised floor, with a foot attachment whose toe portion is sharp-shod on its upper surface, said tongs being pivoted at a lower joint to an upwardly-bent end of said floor, said manually-operated member being pivoted to the lower end of said tongs, and said foot being pivoted by its upper end to the upper end of said tongs, said toe portion of said foot extending thru, and plying within a longitudinal slot in a vertical groove in the one complete end wall of said inner casing, 80 said slot registering with an opening in said floor into which said toe drops, means being provided whereby said pivoted members are guided and held in alignment relative to the casings of said box, and to each other. 95

5. In a pocket match box, the combination of an inner casing with a raised floor, said casing being attached by its lower rim to said floor, and having side walls and one end wall complete, said end wall containing a 100 vertical groove with a longitudinal slot therein which registers with an opening in said floor, the free ends of said side walls being bent inwardly, but not opposite each other, to form an incomplete end wall of 105 said inner casing.

All of which parts and combinations claimed, I believe, are substantially as described and illustrated.

ARTHUR M. BENNER.
